UNITED STATES PATENT OFFICE.

HENRY R. ENGLISH, OF JACKSON, MISSOURI.

DESIGN FOR A GAME-STANDARD.

SPECIFICATION forming part of Design No. 30,310, dated March 7, 1899.

Application filed August 18, 1898. Serial No. 688,930. Term of patent 7 years.

To all whom it may concern:

Be it known that I, HENRY R. ENGLISH, a citizen of the United States, residing at Jackson, in the county of Cape Girardeau and State 5 of Missouri, have invented and produced a new and useful Design for a Game-Standard, of which the following is a specification.

This invention is a new and useful design for a game-standard, the essential feature residing in the peculiar shape of the various parts, as hereinafter fully described.

The drawing hereunto annexed shows my invention in perspective.

Referring to the drawing, A indicates an 15 open ring, and B a vertical standard depending from one end of said ring. At the end of

said standard is produced a bend C, whereby an arm D is provided, which is continued in the form of a circle, as shown at E, after having been bent at F. In this manner I provide 20 an open circular base, a central vertical support, and an open circular top or rest portion.

Having thus described my invention, what I claim as new, and desire to secure by Letters 25 Patent of the United States, is—

The design for a game-standard, substantially as herein shown and described.

HENRY R. ENGLISH.
